(57) **CLAIM**

The ornamental design for a drink pusher glide, as shown and described.

DESCRIPTION

FIG. 1 is a top perspective view of a drink pusher glide, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is a top perspective view thereof of another embodiment;

FIG. 11 is a bottom perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is an enlarged detail view of area 18 in FIG. 10. The broken lines in the drawings illustrate the portions of the drink pusher glide, which form no part of the claimed design.

The dash-dot-dash broken lines encircling the enlarged views are for annotative purposes only and form no part of the claim thereof.

The dash-dot-dot-dash broken lines depict boundaries of the claimed design.

1 Claim, 18 Drawing Sheets
